TAKEDOWN TYPE SWING-OUT-OF-THE-WAY WALL BRACKET

Robert E. McLean, Fort Benning, Ga.

Application November 6, 1946, Serial No. 708,169

8 Claims. (Cl. 248—289)

1

This invention relates generally to the class of supports and pertains particularly to improvements in wall-attached brackets designed for supporting kitchen articles such as rotary or crank operated can openers.

A principal object of the present invention is to provide a pivoted or swingable take-down type of wall bracket comprising an arm portion and a pivoted portion to which the arm is removably connected, with means for positively locking the arm portion in operative position, in a novel manner, whereby such arm portion will be firmly held against swinging movement and against vertical movement regardless of the amount of force or pressure which may be applied thereto in connection with the operation of any unit supported thereby such, for example, as a crank operated drive wheel type can opener.

A further object of the invention is to provide a pivoted or swingable take-down type wall attached support of the character stated wherein the arm portion when placed in a prescribed angular position with respect to a wall-attached plate portion and a hinge element carried thereby, may be readily applied to or removed from such hinge portion and will then be firmly locked in position against swinging movement and against up and down movement when the arm is swung to a position substantially perpendicular to the wall-attached plate.

Still another object of the invention is to provide in a take-down, swing-out-of-the-way type wall bracket, a novel spring actuated latching mechanism which functions automatically to secure the arm portion of the structure in operative or working position when such arm portion is moved into a position perpendicular to a wall-attached plate but which must be manually actuated when it is desired to swing the arm portion out of such perpendicular position for the purpose of placing the arm portion to one side in an out-of-the-way inoperative position or to remove it entirely from connection with the wall-attached plate.

The invention will be best understood from a consideration of the following detailed description taken in connection with the accompanying drawings forming a part of the specification with the understanding, however, that the invention is not confined to a strict conformity with the showing of the drawings but may be changed or modified so long as such changes or modifications mark no material departure from the salient features of the invention as expressed in the appended claims.

2

In the drawings:

Figure 1 is a view in top plan of a wall bracket structure constructed in accordance with one embodiment of the present invention, showing the removable arm in a position where it may be disengaged from the hinge plate or locked in operative position by being swung to a position perpendicular to the wall-attached plate.

Figure 2 is a view in top plan of the structure shown in Figure 1, showing the relative positions of the parts when the bracket arm is locked against removal from the wall-attached plate, and against swinging movement.

Figure 3 is a view in front elevation, the arm being in transverse section.

Figure 4 is a sectional view taken substantially on the line 4—4 of Figure 2.

Figure 5 is a sectional view taken substantially on the line 5—5 of Figure 2.

Figure 6 is a view in top plan of a wall bracket constructed in accordance with a second embodiment of the present invention.

Figure 7 is a view in front elevation, the arm being in transverse section.

Figure 8 is a sectional view taken substantially on the line 8—8 of Figure 7.

Figure 9 is a sectional view taken substantially on the line 9—9 of Figure 7.

Figure 10 is a view in side elevation of the hinge plate per se.

Figure 11 is a view in front elevation of the hinge plate per se.

Referring now more particularly to the drawings and especially to Figures 1 to 5 inclusive the numeral 10 generally designates a plate body which is designed to be secured against the face of a wall or other suitable supporting structure and is, therefore, provided with suitable apertures 11 for the reception of mounting screws 12 or other fastening elements.

The plate 10 is folded transversely to form a hinge sleeve 13 and the two forwardly extending contiguous portions 14 which together form a rigid forwardly projecting rib.

The two portions 14 are firmly secured together to form the rigid forwardly projecting rib or flange between the hinge sleeve 13 and the plate 10, by passing therethrough the rivets 15. As shown the fold in the plate 10 is disposed to one side of the transverse center of the plate thus making the plate longer upon one side of the portions 14 than upon the other. Also the sleeve 13 is set slightly to one side of the plane of the contacting spaces of the portions 14, the center

of the sleeve being moved away from the longer end of the plate.

The rivets 15 are finished upon the ends nearest to the longer end portion of the plate, with the relatively large or heavy heads 16, the function of which will be hereinafter described.

The numeral 17 designates the hinge plate which has the ears 18 and 19 formed integral with and extending at right angles from its two ends. These ears 18 and 19 are in spaced parallel relation and are adapted to receive between them the hinge sleeve 13 as shown in Figure 4. The ears are provided with apertures 20 and through these apertures and through the sleeve 13 extends the hinge pin 21, the upper and lower ends of which are enlarged or provided with the heads 22 which engage the adjacent outer surfaces of the ears of the hinge plate, whereby to maintain the hinge pin in position.

As shown the hinge plate ear 19 is of substantially the same width as the plate 17 whereas the ear 18, which is at the top of the hinge sleeve 13, is of reduced width.

The numeral 23 designates the bracket arm, the forward end portion of which is broken away. At its inner or rear end the bracket arm 23 is shaped to provide the terminal laterally offset guide 24, at opposite sides of which are formed the opposed or facing channels 25 which receive the opposite longitudinal or vertical edges 26 of the hinge plate 17.

The channels 25 have the inturned opposing lips 27 and 28, the space between which is only slightly greater than the width of the top ear 18 but is less than the width of the bottom ear 19. Accordingly it will be seen that when the guide 24 is applied to the hinge plate 17 with the opposite longitudinal edges 26 of such plate engaging in the channels 25, the lower ends of the lips 27 and 28 will rest upon the ear 19.

The lip 28 of the guide 24 is provided with keeper recesses 29 of the same number as the rivet heads 16 and positioned to receive such heads when the arm 23 is swung to a position where it is perpendicular to the face of the plate 10, as shown in Figure 2. Thus it will be seen that when the arm is in this position the engagement of the rivet heads 16 in the keeper recesses 29 prevents the arm being moved upwardly on the hinge plate.

The outer end of the longer portion of the wall plate 10 or, in other words, the end of the plate nearest to the rivet heads 16, is formed to provide the forwardly projecting flange surface, the inner side of which has the channel 31 formed therein and facing the rivet heads 16.

Adjacent to the channel 31 the plate 10 has secured therein the forwardly projecting pins 32, the inner ends of which are reduced as indicated at 33 for engagement in suitable apertures in the wall plate 10.

The numeral 34 designates a latch plate which has spaced apertures 35 to loosely receive the pins 32. These pins 32 are headed on their forward ends to maintain the latch plate 34 in position and the outer vertical edge of the latch plate has loose engagement in the channel 31 as shown in Figures 1 and 2.

The inner side or edge of the latch plate 34 is extended to provide the tongue 36. The width of the keeper plate transversely through the tongue 36 is such that when the plate is in parallel relation with the wall plate 10 and the arm 23 is perpendicular to the wall plate as shown in Figure 2, the free vertical edge of the tongue 36

will lie close to the side of the guide 24 and the opposite vertical edge of the latch plate will be positioned in the channel 31. Thus it will be seen that when the latch plate is in this position and the arm 23 is in the position stated, it will oppose turning or swinging of the arm and the hinge plate on the axis of the pivot pin 21. Since there is a substantial clearance between the latch plate 34 and the face of the wall plate 10 it will be seen that the latch plate can be rocked on its supporting pins 32 sufficiently to move the tongue 36 rearwardly and allow the rear corner of the guide 24 to swing past the latch plate.

In order to maintain the latch plate 34 in forward position upon the pins 32 a spring means is mounted upon the pins 32 which, in the form here illustrated, comprises a relatively thin metal plate 37 placed behind the latch plate 34 and having suitable apertures to receive the reduced portions of the pins 32 whereby such spring plate is firmly secured against the front face of the wall plate 10. The spring plate 37 has a forwardly curving spring tongue 38 engaging behind the latch plate tongue 36 thereby normally urging oscillation of the latch plate to a spaced parallel relation with the face of the wall plate 10, as it is shown in Figure 2.

While the spring means for controlling the latch plate 34 is here shown as being in the form of a leaf spring it is to be understood that the invention is not restricted to this specific structure as it will be readily apparent that coil springs might be telescoped onto the pins 32 to engage between the latch plate 34 and the wall plate 10.

In the embodiment of the invention shown in Figures 6 to 11 inclusive the form of the arm, hinge plate and pivot for the hinge plate is the same as in the first described form of the invention. Accordingly these parts will only be generally referred to. The wall plate is generally designated 10a and is shaped or folded to provide the portions 14a which are secured together by the rivets 15a. In the sleeve 13a which is formed as an integral part of the wall plate, the pivot pin 21a maintains in position the hinge plate 17a through the medium of the upper and lower ears 18a and 19a which are of the same form as the ears 18 and 19. This hinge plate is illustrated in detail in Figures 10 and 11.

In the modified embodiment of Figures 6 to 11 the bracket arm is designated 23a and the guide which receives the opposite vertical edges of the hinge plate 17a, is generally designated 24a.

In this modified construction it will be seen that the portions 14a are of slightly less width than the portions 14 and therefore position the hinge sleeve 13a nearer to the forward face of the wall plate 10a. The reason for this is that the latching means about to be described, for holding the arm 23a in locked position perpendicular to the wall plate 10a, lies directly against the front face of the wall plate 10a instead of being spaced therefrom as is the latching plate 34 and tongue 36.

The plate 10a carries adjacent to the right hand vertical edge the pivot stud or rivet 39. Mounted upon this stud 39 for oscillation, is the latch plate 40, the top edge of which carries the forwardly projecting ear 41. The end of the latch plate 40 which functions to maintain the arm 23a in locked position, is arcuately cammed as indicated at 42 and this curved or arcuate edge is designed to swing down against and frictionally engage the outer or right hand side of the guide 24a, when the arm 23a is perpendicu-

lar to the plate 10a, as shown in Figures 6 to 8. When the arm 23a is in this position the inner end of the guide 24a will be in relatively close proximity to the face of the plate 10a and the lip 28a will be in engagement with the adjacent heads 16a of the rivets 15a and therefore cannot be lifted from the hinge plate 17a. Neither can it be swung on the axis of the pivot pin 21a because of the engagement of the latch plate 40 against the adjacent side of the guide 24a.

From the foregoing it will be readily apparent that there is provided in the present invention a bracket structure for mounting upon a wall or other suitable support any one of various types of can openers, wherein the supported article will be firmly held in operative position so that the bracket cannot swing or shift upwardly. However when the supported article is no longer to be used it can be readily swung to one side by manipulating the securing latch whereby to free the arm for turning movement. If the supported article is to be dismounted then after the securing latch is shifted to release the guide at the inner end of the arm, the arm may be swung around and then raised up to be freed from connection with the hinge plate. As will be readily seen this swinging of the arm will disengage the guide from the rivet heads thereby permitting the stated upward movement of the arm on the plate of the hinge.

The present invention provides a take-down type swing-out-of-the-way wall bracket that is easy and simple to operate; that is entirely safe under all conditions of operation; and that is unusually strong, durable, and rigid. The portion of the bracket which is secured to the device to be supported by the bracket is of such conformation as to store easily and without hazard, and by reason of its size and construction can be economically produced as a part of any number of various instruments or devices for use with the portion remaining attached to the wall or other support.

I claim:

1. A support comprising a mounting plate, a member pivotally coupled with the plate and including a part having two parallel edges parallel to the pivot axis for said member, an arm, means at one end of the arm for slidably receiving said edges whereby the arm may swing with the member to a position in which is it perpendicular to the plate, means for locking the arm against movement longitudinally of said parallel edges when the arm is swung to the said position perpendicular to the plate, and means for securing the arm against swinging movement from the position in which it is perpendicular to the plate.

2. A support comprising a mounting plate, a hinge plate, a pivot connection between the hinge plate and the mounting plate, an arm, means forming a sliding coupling between the arm and the hinge plate whereby the arm and hinge plate swing as a unit on said pivot, the arm being adapted to be swung to a working position in which it is perpendicular to the mounting plate, coacting means between the mounting plate and the arm functioning to prevent sliding disconnection of the arm from the hinge plate when the arm is in said working position, and a latch element carried by the mounting plate and adapted to engage and hold the arm against swinging movement when the arm has been swung to the said working position.

3. A support of the character stated in claim 2,

wherein the said coacting means between the mounting plate and the arm comprises a rivet having a head portion and supported on the mounting plate, and a keeper recess formed in a part of the arm for the reception of the rivet head.

4. A support comprising a mounting plate, a hinge sleeve, means joining the hinge sleeve to the mounting plate, a pivot pin extending through said hinge sleeve, a hinge plate disposed lengthwise of the sleeve and attached at its ends to said pivot pin, an arm having an end formed to provide a guide, the guide being designed to slidably receive said hinge plate whereby to couple the arm and hinge plate together for swinging movement as a unit on the axis of said pin, said arm having a working position in which it is perpendicular to the mounting plate, means locking the arm against disconnection from the hinge plate when the arm is in said working position, and a shiftable latch carried by the mounting plate and adapted to engage and hold said arm against swinging movement when the arm is swung to the said working position.

5. A support comprising a mounting plate having a rigid forwardly extending rib-like portion, a hinge sleeve integral with said rib-like portion, a pivot pin within and extending through said sleeve, a hinge plate extending lengthwise of the sleeve and having laterally extending end ears between which the sleeve is engaged, said ears being connected with the adjacent ends of the pin, an arm, means at one end of the arm forming a pair of opposed channels extending transversely of the arm, the channels being adapted to receive the longitudinal edges of the hinge plate, means limiting the sliding movement of the channels on the hinge plate in one direction, said arm having a working position in which it is perpendicular to the mounting plate, the arm when in the said working position having a portion adjacent to one side of the said rigid rib-like member, an element upon the said one side of the rib-like member adapted to engage in a recess in the adjacent end of the arm when the arm is in working position, and a latch member carried upon the mounting plate and adapted to engage and hold the arm in the said working position and against swinging movement with the hinge plate about the axis of said pin.

6. A support of the character stated in claim 5, in which said latching means comprises a latch plate, means carried by the mounting plate and supporting the latching plate in spaced relation with the mounting plate, and yieldable means between the latching plate and the mounting plate and normally urging the latching plate outwardly to the said position in which it holds the arm against swinging movement.

7. A support of the character stated in claim 5, wherein said latching means comprises a latching plate, pins carried by the mounting plate and engaging loosely in apertures in the latching plate, the mounting plate having an end flange provided with a channel in which an edge of the latching plate is loosely engaged, the opposite edge of the latching plate being adapted to oppose a side of the arm when the arm is in working position, and spring means interposed between the latching plate and the mounting plate to normally urge the latching plate outwardly from the mounting plate and to a position where it may engage the said side of the arm.

8. A support of the character stated in claim 5, with a latching plate pivotally mounted upon the mounting plate and adapted to be oscillated

to a position in which an edge is brought into opposed relation with a side of the arm to secure the arm from swinging movement from the said working position.
